UNITED STATES PATENT OFFICE.

ALEXANDER BRYANT AND WILLIAM J. CROW, OF NEW YORK, N. Y.

SAFETY-VALVE FOR EXPANSION-PIPES.

SPECIFICATION forming part of Letters Patent No. 449,243, dated March 31, 1891.

Application filed October 9, 1890. Serial No. 367,509. (No model.)

To all whom it may concern:

Be it known that we, ALEXANDER BRYANT and WILLIAM J. CROW, both of the city, county, and State of New York, have invented 5 a new and useful Improvement in Safety-Valves for Expansion-Pipes; and we do hereby declare that the following is a full and exact description thereof, reference being had to the accompanying drawings, and to the letters of 10 reference marked thereon, making a part of this specification.

Our invention relates to a device for preventing a flow and waste of water through the boiler in the water-supply system of a dwelling-house or other building by reason of an 15 undue pressure in the cold-water feed-pipe.

In the approved systems of hot-water supply for a city house it is customary to carry an open pipe, known as an "expansion-pipe," 20 from the top of the boiler to a point above the supply-tank or highest point of delivery. This expansion-pipe operates as a safety device to guard the boiler against the possibility of undue pressure by reason of a generation 25 of steam therein, provision being made for the water which may overflow from the pipe usually by carrying the end of the pipe above the supply-tank, so that it may discharge therein. Where, however, as is usually the 30 case, the boiler is connected directly with the street-main, it often happens that unless pains be taken to shut off this connection at night the increased pressure in the main which then occurs by reason of the lessened demand 35 for water operates to produce a constant flow through the boiler and out of the upper end of the expansion-pipe, so that in a short time the hot water in the boiler will all be discharged therefrom and replaced by the 40 cold water delivered from the main.

The object of our invention is to prevent by an automatic device this discharge or flow of water through the boiler under this increase of pressure; and it consists in the combination, with the boiler, its supply-pipe, and 45 expansion-pipe, of a vertically-moving valve fitted to move outwardly against a suitable seat in the end of the expansion-pipe and thereby effectually close the pipe, and which 50 will drop back automatically from its seat by reason of its weight alone, so as to open the

pipe. This cut-off valve is made to close automatically by means of an inverted cup or hollow cylinder upon which the valve is carried, and which is fitted to play so loosely 55 within the pipe as to permit an escape of air around it when the valve has dropped from its seat, but which will be carried up as a float by a column of water rising therein, and thereby lift the valve against its seat, so as to 60 close the pipe and prevent an escape of the water therefrom, and is constructed with a central vent-passage through it, which is closed by an auxiliary valve automatically 65 closed by a spring and opened when an excess of pressure occurs in the hollow cylinder by means of a suitable float fitted in said cylinder, all as hereinafter described and claimed.

In the accompanying drawings, Figure 1 represents in elevation a hot-water boiler with 70 its supply and expansion pipes, the latter fitted with our automatic cut-off valve. Fig. 2 is an elevation upon an enlarged scale of the cut-off valve with the top deflecting-hood removed; and Fig. 3, a central longitudinal 75 section thereof in line xx of Fig. 2 with the hood in place.

A represents the hot-water boiler in the water-supply system of a building, connected in the usual manner by a circulating-pipe B 80 with the water-back in a range or other heating apparatus.

C is the cold-water-supply pipe connected directly with the main.

D is the expansion-pipe extending as is 85 usual from the top of the boiler A to a point above the highest level of the delivery-pipes, and preferably over the tank E.

F represents our automatic cut-off valve fitted upon the upper end of said expansion- 90 pipe. This valve is constructed of a cylindrical shell or casing F', contracted at its outer upper end, as shown in Fig. 3, so as to form an annular seat or offset g about the opening in said end, and which is exteriorly 95 threaded at its opposite lower end to receive a coupling-ring H, serving to couple it in the customary manner with a ferrule K, by which to connect it with the end of the expansion-pipe D. The ferrule K is of smaller diameter than the casing F', so as to form with the latter when the two are united an internal 100

offset t . A washer L, interposed between the casing and ferrule, as shown in Fig. 3, projects inwardly to rest upon this offset.

Within the casing F' is fitted a hollow cylinder N of thin metal, closed at its upper end and left free to play loosely within the casing, so as to drop and rest by its weight alone upon the washer L on the end of the ferrule. The diameter of this cylinder N is such as to 5 permit a passage of air about its periphery through the casing, its lower end being notched, as at r , to establish communication between the expansion-pipe D and said air-passage. An open-ended tubular pin S' is secured 10 upon the outer upper end of the hollow cylinder N, and a rubber valve P is fitted upon said pin and confined by a nut T. This valve P is of sufficient diameter to seat itself when uplifted for the purpose against the 15 contracted end g of the casing F', so as to close thereby the opening in the end of the pipe. An auxiliary valve a is fitted to seat itself upon the upper end of this central tube S', said valve being connected by a central spindle b, extending down through the 20 tube S', with the closed end of an inverted cup N' playing freely within the cylinder N. The valve a is kept automatically closed by means of a spring W, interposed between the 25 cup N' and the top of the cylinder N, the strength of said spring being so adjusted as that it will not permit the valve a to open under the pressure which will operate to close the valve P, but will yield if, after said valve 30 P is closed, the pressure becomes so great as to endanger the boiler or pipes, and, yielding, will thereby allow the valve a to open and relieve the pressure.

A hood U is fitted over the top of the valve-casing F' to deflect any water which may be forced out through the valve F and cause it to drop back immediately into the tank E, over which the valve is located.

In the operation of our invention, when the 45 water-pressure in the boiler A is normal, so that the level of the water in the expansion-pipe D is below the outer end of the pipe, the cylinder N, carrying the valve P in the valve-casing F', secured upon the outer end of the 50 pipe, will drop of its own weight and rest with its lower notched edge upon the washer L, and thereby leave the aperture in the outer end of the pipe free. With the valve P in this position free vent is afforded to the air 55 in the upper end of the expansion-pipe D through the notches r in the lower edge of the cylinder N and the narrow space left between said cylinder and the inner periphery of its casing F', so as to permit the water-level in the pipe D to rise and fall freely, as 60 in an open pipe. When, however, the pressure of the water-supply to the boiler has so

far increased as to cause the water to rise above the level of the valve, the water rising under the cylinder N will by reason of the 65 air which will be caught and confined within said cylinder cause it to rise, and in rising will cause the valve P to close the open end of the casing F', and thus effectually prevent an outflow of water through it, so that a circulation of the water-supply into and through the boiler and out through the expansion-pipe cannot take place and the discharge by this means of the hot water in the boiler through said expansion-pipe be entirely prevented. 75

An undue pressure in the boiler and expansion-pipe after the cut-off valve P is closed from a generation of steam in the boiler or other cause is prevented by the operation of 80 the central auxiliary or safety valve a.

We claim as our invention—

1. The combination, in the water-supply system for a building, with the hot-water boiler, its cold-water-supply pipe and its expansion-pipe, a valve-casing fitted upon the upper end of the expansion-pipe and having a contracted valve-opening at the top, and a valve adapted to close said opening carried upon the upper closed end of a hollow cylinder left open at its lower end and fitted to play loosely within said casing, of a central vent-opening through the valve, a spring-actuated valve closing said vent, and an auxiliary float placed within the hollow cylinder 95 and attached to the vent-valve to open it against the stress of its spring, substantially in the manner and for the purpose herein set forth.

2. The combination, with the expansion-pipe D, the valve-casing F', fitted thereto, having an opening in its outer end, and the hollow cylinder N, playing loosely in said casing, of the central tube S', secured to project from the upper closed end of the cylinder N, the rubber valve P, encircling said tube and adapted to close the outer end of the valve-casing when lifted thereto, a spindle b, fitted loosely in the tube, a valve a, fitted upon the outer end of the spindle to drop upon and close the 110 end of the tube, an inverted cup or float N', playing loosely with the cylinder N and secured to the spindle, and an interposed spring W, all substantially in the manner and for the purpose herein set forth. 115

In testimony whereof we have signed our names to this specification in the presence of two subscribing witnesses.
